SEMICOFFER OR SHIP CAISSON

Hans Gerdes, Wilhelmshaven, Germany

Application November 10, 1936, Serial No. 110,167
In Germany November 12, 1935

6 Claims. (Cl. 61—63)

It has been observed that in the case of sheet pilings very strong corrosion often takes place under water as the pilings are not sufficiently protected against corrosion. Experience has shown that the corrosion is strongest at a certain distance below the normal water level. In a North Sea port, for example it has been noticed that the corrosion zone was greatest in iron structures within the section of the harbor partitioned off by seal locks at about 1 meter below the normal, relatively constant water level, and that in the case of iron structures outside the sea locks, where the water level varies daily on an average about 3½ meters owing to the tide, the greatest corrosion occurred at about 1 meter below the mean low water level.

Hitherto it has not been possible to protect sheet pilings under water against corrosion after their erection. Furthermore no serious endeavours have been made for the preservation below water because the general opinion was that a considerable weakening through corrosion need not be feared. However, according to the latest observations above set forth this is not the case and experts are gradually becoming convinced that in many instances something radical must be undertaken to preserve the sheet pilings below water. This is the more necessary because the points under water which are most strongly attacked by corrosion coincide with those portions of the sheet piling subjected to the greatest bending moments. Precisely these points are least suitable to stand a reduction in cross-section and the resultant reduction in strength of the iron remaining standing.

It is known that the coat of protective painting applied on the water side before the ramming does not remain effective for a long period, more particularly in the case of aggressive waters (sea water), and when living creatures (*Balanoids*, *Balanus balanoides* L.) are present, which destroy the coating, thus enabling the water to come into contact with the iron. As long as it is not possible to provide an effective protection against corrosion of the portions of the sheet piling below water, the walls of the iron sheet piling must be made thicker than would otherwise be necessary, so as to take into consideration this weakening effect due to corrosion. In the case of important structures substitute structures may become prematurely necessary, because nothing is known concerning the extent of corrosion. Finally, the question of the protection against destruction due to corrosion must have an influence on the selection of the material in planning.

The new method for preserving iron sheet pilings and other structural parts below water consists in draining off the water from the surfaces of the sheet pilings in question by means of a coffer or caisson. Experience has shown, that a sufficiently long time is required for thoroughly drying the sheet pilings, if necessary with hot-air, removing the rust (with sand blast) and painting them, to obtain effective preservation. The coffer or caisson is provided with floats to enable it to be easily brought into the position for use at a minimum expense; an arrangement is also provided on the coffer for receiving ballast (preferably ballast tanks). When the coffer is in horizontal floating position all packing surfaces can be easily fitted and repaired. At the place of use the coffer is brought into its vertical floating position and sunk to the desired depth by flooding a ballast tank. The depth of immersion can be easily regulated by operating the flooding valves and the shut-off devices on air-pipes leading to the tanks. The coffer, when in vertical floating position, is brought tightly against the piling and emptied by bilge pumps preferably mounted on the coffer. The coffer is pressed against the piling by the external water pressure, so that a tight closure is produced. It is, however, necessary to counteract the upward pressure acting on the bottom of the coffer. This is effected by further flooding all the existing ballast tanks to the required extent. It is particularly important that the coffer be sufficiently loaded by ballast water as the wall friction between the smooth piling and the packing materials on the coffer (rubber, hemp, mats or the like) is slight. The buoyancy is counteracted by the constructional weight of the coffer and of the ballast water admitted. If necessary, the ballast tanks must extend slightly above the water level to allow additional quantities of ballast water to be filled therein by a water feed pipe or by a pump. Further details are shown in the accompanying drawing showing the coffer illustrated by way of example, in which

Fig. 1 is a vertical section of the coffer fitted on a sheet piling.

Fig. 2 is a horizontal sectional view taken on the line 2—2 of Fig. 1.

Fig. 3 is a front elevation of the device shown in Fig. 1.

Fig. 4 is a horizontal sectional view similar to Fig. 2 but showing a modified form of construction of the coffer.

The coffer *a* has on its outer side at its upper end peripheral float and ballast tanks *b*. Fur-

thermòre, floating boxes b' , subdivided by horizontal bulkheads b^2 , extend along the entire height of the longitudinal sides of the coffer and serve at the same time as capsizing tanks.

5 Fig. 3 shows for example a subdivision of each tank into two compartments b^3 by a horizontal bulkhead b^4 . The open side has a packing frame c removably fixed on the coffer a and bearing against the surface of the sheet piling d . When 10 the coffer has been brought in the required position against the sheet piling and suitably anchored, the space c^2 provided between the structure—the outer surface of the sheet piling d —and the coffer a is pumped dry, the ballast tanks 15 being at the same time filled, so that the coffer bears tightly against the structure by means of the packing frame c and is secured against emersion. The necessary work—for example painting of the exposed portion of the sheet piling is carried out through the packing frame c within the 20 protection of the space thus formed.

To prevent the stock of coffers necessary for accelerating the work from becoming too large in the case of high sheet piling the invention provides means shown in Fig. 4 for externally shutting off the loaded packing frame on the spot by a plate g to enable the coffer to be removed and the surface to dry or harden. In this manner the painted surface will be protected by the space 25 formed between the packing frame and the plate.

A packing frame c^3 of this construction with inserted removable plate g is shown in horizontal section in Fig. 4.

The packing frame c^3 differs from the frame c 35 in Fig. 1, in that it is provided with a continuous channel f designed to accommodate the plate g . This channel may be lined with rubber or other suitable material (not shown) to provide a watertight channel for the plate g .

40 The packing frame c^3 as well as the frame c , are provided with extensions c^1 which are adapted to the undulating shape of the sheet piling. These extensions c^1 may be secured to the frames by bolts m as shown in Fig. 4. In this figure, the 45 bolts m extend through the extensions c^1 , frame c^3 and channel member f . It will also be observed in this figure of the drawing that these bolts do not extend through the plate g but are arranged beneath said plate.

50 In this modification of the invention, the coffer a^1 is detachably connected to the frame c^3 by bolts h . These bolts may be loosened from the interior of the coffer after the painting is completed and before the plate g is inserted in the channel.

55 The complete removal of the bolts h may be accomplished from the exterior of the coffer, after the plate g has been inserted in the channel f . By removing the bolts h the coffer is disconnected from the frame and may be transferred to another location for a further painting operation.

60 After the coffer a^1 has been removed from the frame c^3 , the plate g in the channel f will maintain the frame pressed against the piling due to the water pressure exerted against said plate.

65 However, since the plate g must withstand a considerable water pressure, I preferably provide said plate with supports i which bear against the ribs k of the piling. To prevent the supports i on the plate from adhering too tightly against the sheet piling, it is advisable to provide strips l of wool felt board, sheet metal or the like between the supports i and the ribs k of the piling.

70 With this arrangement it will be seen that the freshly painted surface of the piling may be protected by the space formed between the packing

frame c^3 and the plate g until the paint has dried or hardened. When the surface has dried or hardened, the space between the plate and the piling is filled with water so that the plate can easily be pulled out of the water.

5

I claim:

1. A coffer of the class described for carrying out work on submerged structures, comprising, a bottom wall, spaced vertical walls secured to said bottom wall, partitions connecting said walls to form a plurality of fluid-tight ballast chambers, said vertical walls being spaced from the innermost edge of the bottom wall to form a vertical working space, and a packing member secured to said walls, said packing member forming a frame 15 comprising a lower member conforming to the contour of the submerged structure, and a pair of spaced vertical members secured to said lower member, and a removable plate slidably mounted on said frame and spaced from the submerged 20 structure.

2. A coffer of the class described for carrying out work on submerged structures comprising, a bottom wall, spaced vertical walls secured to said bottom wall, partitions connecting said walls to form a plurality of fluid tight ballast chambers, said vertical walls being spaced from the innermost edge of the bottom wall to form a vertical working space, and a packing member secured to said walls, said packing member forming a frame 30 comprising a lower member conforming to the contour of the submerged structure, a pair of spaced vertical members secured to said lower member, said last mentioned members having cut-away portions defining a channel, and a removable plate slidably mounted in said channel and forming with said vertical members and said lower member a fluid tight joint, said plate being spaced from the submerged structure.

3. A coffer of the class described for carrying out work on submerged structures comprising, a bottom wall, spaced vertical walls secured to said bottom wall, partitions connecting said walls to form a plurality of fluid tight ballast chambers, said vertical walls being spaced from the innermost edge of the bottom wall to form a vertical working space, and a packing member secured to said walls, said packing member forming a frame comprising a lower member conforming to the contour of the submerged structure and a pair 45 of spaced vertical members secured to said lower member, a removable plate slidably mounted on said frame, and spaced from the submerged structure, and supporting members secured to said plate and interposed between said submerged 50 structure and said plate.

4. A coffer of the class described for carrying out work on submerged structures comprising, a bottom wall, spaced vertical walls secured to said bottom wall, partitions connecting said walls to form a plurality of fluid tight ballast chambers, said vertical walls being spaced from the innermost edge of the bottom wall to form a vertical working space, and a packing member secured to said walls, said packing member forming a frame 65 comprising a lower member conforming to the contour of the submerged structure and a pair of spaced vertical members secured to said lower member, a channel member secured to said frame and spaced from the submerged structure, a removable plate slidably mounted in said channel member, supporting members secured to said plate and adapted to abut against the submerged structure, and yielding means lining the abutting surface of said supports.

75.

5. A coffer of the class described for carrying out work on submerged structures having non-planar surfaces, comprising a bottom wall, spaced vertical walls secured to said bottom wall, partitions connecting said walls to form fluid tight ballast chambers, said vertical walls being spaced from the innermost edge of the bottom wall to form a vertical working space, a packing member shaped to fit against said non-planar surface 5 at the bottom wall and interposed between said walls and the submerged structure, and fastening means for disconnecting said walls from said packing member.
10. A coffer of the class described for carrying out work on submerged structures having a non-planar surface, comprising a bottom wall, spaced vertical walls secured to said bottom wall, said vertical walls being spaced from the innermost 5 edge of the bottom wall to form a vertical working space, a packing member shaped to fit against said non-planar surface at the bottom wall and interposed between said walls and the submerged structure, and fastening means for disconnecting 10 said walls from said packing member.

HANS GERDES.
